CLAIM

The ornamental design for a game controller, as shown and described.

DESCRIPTION

FIG. 1 is a front perspective view of a game controller showing our new design;

FIG. 2 is a rear perspective view thereof;

FIG. 3 is a bottom view thereof;

FIG. 4 is a top view thereof;

FIG. 5 is a right side view thereof;

FIG. 6 is a left side view thereof;

FIG. 7 is a front view thereof; and,

FIG. 8 is a rear view thereof.

The broken lines, in FIGS. 1-8, depict portions of the “game controller” that form no part of the claimed design.

1 Claim, 8 Drawing Sheets(56)
